UNITED STATES PATENT OFFICE.

ALFRED A. KOHN, OF MONTGOMERY, ALABAMA.

DESIGN FOR A SHOE.

SPECIFICATION forming part of Design No. 26,663, dated February 16, 1897.

Application filed November 11, 1896. Serial No. 611,761. Term of patent 14 years.

To all whom it may concern:

Be it known that I, ALFRED A. KOHN, of Montgomery, in the county of Montgomery, State of Alabama, have invented and produced a new and original Design for Shoes, of which the following is a complete specification, reference being had to the accompanying drawing.

The figure is a perspective view of a lace shoe, showing my design.

The leading feature of my design consists in a shoe having a finishing-piece provided with a series of ornamental figures or patterns upon each side of the front opening, said figures being diamond-shaped or rectangular in contour and separated from each other by small circular perforations, as shown.

Referring to the figures on the drawing, 1 indicates the sole of my shoe, 2 the heel, and 3 the upper.

Secured to the upper around the front opening is the finishing-piece 4, which is somewhat broadened at the mouth of the shoe and terminates in a tapered end 6.

The finishing-piece 4 is provided with a series of circular and diamond shaped perforations 8 and 9, respectively, which extend on both sides of the front opening. I also provide a reinforcing back piece 5 and a perforated toe-piece 7 as forming a complete finish to my shoe.

What I claim is—

The design for shoes herein shown and described.

In testimony of all which I have hereunto subscribed my name.

ALFRED A. KOHN.
